UNITED STATES PATENT OFFICE.

FREDERICK EGGE, OF BRIDGEPORT, CONNECTICUT.

DESIGN FOR A LACE-FASTENER.

SPECIFICATION forming part of Design No. 28,302, dated February 15, 1898.

Application filed June 26, 1897. Serial No. 642,542. Term of patent 14 years.

To all whom it may concern:

Be it known that I, FREDERICK EGGE, a citizen of the United States, residing at Bridgeport, Connecticut, have invented a new and original Design for Lace-Fasteners, of which the following is a specification.

The accompanying drawing is an enlarged perspective view of a lacing-hook, showing my design.

10 The leading or characteristic feature of my design comprises a lace-fastener in the form of the frustum of a hollow cone, which is surmounted on its larger diameter by a flanged projection, out of which at a point in its pe-

riphery arises a short standard, which expands into an open loop in a plane above the flanged projection and over the same.

15 1 is the frustum of the hollow-cone part; 2, the flanged projection; 4, the standard, and 3 the open loop.

20 What I claim is—

The design for the lace-fastener herein described and shown.

FREDERICK EGGE.
